Patented Sept. 20, 1921.

FIG. 1.

FIG. 3.

FIG. 4.

Inventor
Ainsley L. Jones 2nd
By his Attorney
Edgar V. Lester

UNITED STATES PATENT OFFICE.

AINSLEY L. JONES, 2D, OF MARINERS HARBOR, NEW YORK.

STOP DEVICE FOR ELECTRIC-RAILWAY TRAINS.

1,391,323.

Specification of Letters Patent. Patented Sept. 20, 1921.

Application filed January 22, 1921. Serial No. 439,068.

To all whom it may concern:

Be it known that I, AINSLEY L. JONES, 2d, a citizen of the United States, and residing at Mariners Harbor, Staten Island, in the county of Richmond and State of New York, have invented certain new and useful Improvements in Stop Devices for Electric-Railway Trains, of which the following is a specification, such as will enable those skilled 10 in the art to which it appertains to make and use the same.

This invention relates to miniature electric railways and the object of the invention is to provide railways of this class with means for 15 stopping the progress of an electric locomotive or car over the track of such railways, said stopping means being preferably in operative connection with a signal post construction located at a predetermined point 20 along the track of the railway, and with this and other objects in view the invention consists in a stop device of the class and for the purpose specified which is simple in construction and operation and efficient in use, 25 and which is constructed as hereinafter described and claimed.

The invention is fully disclosed in the following specification, of which the accompanying drawing forms a part, in which the 30 separate parts of my improvement are designated by suitable reference characters in each of the views, and in which:—

Figure 1 is a plan view of one section of the track of a miniature electric railway with 35 a signal post construction mounted in connection therewith, and showing my improved stop device;

Fig. 2 is a partial section on the line 2—2 of Fig. 1 and indicating the use of my improved stop device;

Fig. 3 is a partial section on the line 3—3 of Fig. 1 with part of the construction broken away;

Fig. 4 is a view similar to Fig. 3 but showing parts in a different position; and,

Fig. 5 a partial section on the line 5—5 of Fig. 1 and on an enlarged scale.

In the drawing I have shown at 10 one section of the track of a miniature electric railway, such for example as a "Lionel" electric railway system, said track section comprising side rails 11 and 12 and a central current carrying rail 13, and said rails are mounted in the form of construction shown

on three transverse ties 14, the rail 13 being 55 insulated from the tie 14 as shown at 15.

The construction of the rail section 10 forms no part of my invention and is merely shown to illustrate one use of my improved stop device for railway systems of the class 60 specified.

I preferably mount in connection with the section 10 a base 16 upon which a part of the rails 11 and 13 are adapted to rest as shown in Figs. 3 and 4, and mounted on the base 65 16 is the standard 17 of a semaphore, the signal arm 18 of which is pivoted to said standard as shown at 19, and said arm carries red and green translucent panels 20 and 21.

Pivoted to the base 16 at one side of the 70 standard 17 is an approximately triangular plate 22 to one corner portion of which is pivoted a rod 23 which is also connected with the signal arm 18, as clearly shown in Figs. 3 and 4 of the drawing. The triangular plate 22 is provided with a backwardly directed finger piece 24 which forms means by which the switch arm may be raised and lowered in the usual manner.

I also mount in connection with the plate 80 22 a forwardly directed rod 25 which passes downwardly through an aperture 26 in the base 16 and then forwardly in a cut-out portion 27 in said base, and is connected with a lever 28 mounted in the cut-out portion 27 85 and pivoted to the base as indicated at 29 in Fig. 1 of the drawing.

In practice, I also mount in connection with one of the rails 11, 12 or 13, preferably the rail 13, a supplemental rail 30 composed 90 of insulated material, and the rail 30 is mounted in connection with the rail 13 by bolts or rivets 31 passed through said rails, said bolts or rivets passing through elongated inclined apertures 32, as clearly shown 95 in Fig. 2 of the drawing, whereby in the movement of the supplemental rail 30, as hereinafter described, said rail will be raised and lowered.

The rail 30 is placed in operative connection with the signal post construction by the means for operating the signal arm 18 thereof or through a rod 33 pivoted to the lever 28 and pivoted approximately centrally of the rail 30, as indicated at 34. The rod 33, in 100 the form of construction shown, extends outwardly through the cut-out portion 27 of the base 16 upwardly over one of the ties 14

and downwardly and transversely beneath the rails 13 and 30, as shown at 35 in Fig. 5 of the drawing. One end portion of the rail 30 is preferably beveled to a slight extent as shown at 36 in Fig. 2 of the drawing.

I am well aware of the fact that signal post constructions involving standards 17 and signal arms 18 as well as the means for operating said arms are old and have been commonly employed in connection with electric railways of the class under consideration, but no means have been provided for stopping a locomotive as it approaches a semaphore or signal post construction, the signal arm or element of which is set at danger, and with my improved supplemental rail which is mounted in connection with the central rail 13 of the track, a locomotive or car approaching a signal post construction, the signal arm or element of which is set at danger, may be stopped, and said locomotive or car automatically started by simply moving the signal arm or element out of danger position, or into position to indicate a clear track.

The above result is accomplished in the following manner. In Fig. 3 of the drawing I have shown a signal arm 18 of a signal post construction in a position which indicates a clear track, and in this position it will be noted that the rail 30, or the top face thereof, is located below the top face of the rail 13 so that an electric locomotive or car, part of which is indicated at 37 in Figs. 3 and 4 of the drawing, or the electric contact rollers 38 thereof, will readily pass over the track section 10 and by the signal post construction which is in the position shown in said figure.

In Fig. 4 of the drawing, I have shown a signal arm 18 of the signal post construction and various other parts in a different position from that shown in Fig. 3, and in which the signal arm 18 is set at danger and the rail 30 of the top face thereof projects beyond the top face of the rail 13 so that when the locomotive or car 37 approaches the track section 10, the contact rollers 38 thereof will pass upwardly over the beveled end portion 36 of said rail and thus onto the top face thereof, in which position the said contact rollers are out of electrical communication with the rail 13 and the circuit to the electric motor of said locomotive is broken.

The two different positions of the rail 30 and rollers 38 are also shown in full and dotted lines in Fig. 2 of the drawing. It will be apparent that the movement of the various parts of the post construction, including the rail 30 from the position shown in Fig. 3 to that shown in Fig. 4 is accomplished by raising the finger piece 24 of the triangular plate 22, and by again depressing this finger piece the parts may be returned to the position shown in Fig. 3, and if a locomotive or car be stopped in the manner

above set out, or by raising the rail 30, it will be seen that said locomotive or car may be again started by simply returning the parts to the position shown in Fig. 3 and shown in full lines in Fig. 2, in which operation the contact rollers 38 are again brought into engagement with the rail 13.

It will also be seen that the rail 30 in addition to acting as means for breaking the circuit through the contact rollers 38 and rail 13 will also act in the manner of a brake to more quickly stop a locomotive or car approaching a signal post construction set at danger.

It will be understood that while I have shown certain details of construction for carrying my invention into effect and have shown the stop device employed in connection with a semaphore that I am not necessarily limited to these specific uses, and various other changes in and modifications of the construction herein shown and described may be made, within the scope of the appended claims, without departing from the spirit of my invention or sacrificing its advantages.

Having fully described my invention, what I claim as new and desire to secure by Letters Patent, is:—

1. A stop device for electric railways of the class described comprising a rail composed of insulating material mounted longitudinally of and in connection with one of the current carrying rails of a railway, and means for moving said insulating rail into position to break the circuit to a locomotive or car as it passes thereover.

2. A stop device for electric railways of the class described comprising a rail composed of insulating material mounted longitudinally of and in connection with one of the current carrying rails of a railway, and means for moving said insulating rail into position to break the circuit to a locomotive or car as it passes thereover, said means being in operative connection with a signal post construction whereby the movement of the signal element of said post construction actuates said insulating rail.

3. The combination with a track section of an electric railway of the class described, of an insulating rail mounted in connection with one of the current carrying rails of said track section, and means for actuating said insulating rail.

4. The combination with a track section of an electric railway of the class described, of an insulating rail mounted in connection with one of the current carrying rails of said track section, and means for actuating said insulating rail, said means being in operative connection with the means for actuating the signal element of a signal post construction.

5. The combination with one of the cur-

- rent carrying rails of a track section of the class described, of an insulating rail movably mounted in connection with said rail the top face of which is normally below the 5 top face of said current carrying rail, and means for actuating said insulating rail to bring the top face thereof a predetermined distance above the top face of said current carrying rail.
- 10 6. The combination with one of the current carrying rails of a track section of the class described, of an insulating rail movably mounted in connection with said rail the top face of which is normally below the 15 top face of said current carrying rail, and means for actuating said insulating rail to bring the top face thereof a predetermined distance above the top face of said current carrying rail, said means being in operative 20 connection with the means for actuating the signal element of a signal post construction.
7. The combination with the track of an electric railway system of the class described, of means for raising the electric 25 contact rollers of a locomotive or car, passing over the track of said railway, to break the circuit to the electric motor of said locomotive or car, said means being in operative connection with the means for actuating the 30 signal element of a signal post construction.
8. The combination with the track of an electric railway system of the class described and a locomotive or car adapted to pass over said track and provided with rail en- 35 gaging electric conducting members, of insulated means for raising said electric con-
- ducting members into inoperative position to break the circuit to the electric motor of said locomotive or car.
9. In a railway system of the class de- 40 scribed provided with a track having current carrying rails and electric conducting members on a locomotive or car adapted to engage a current carrying rail of the track, a stop mechanism comprising insulated 45 means for moving said electric conducting members out of engagement with said rail to break the circuit to and stop the locomotive or car as it passes over a predetermined portion of the track of the railway. 50
10. In a railway system of the class de- 55 scribed provided with a track having current carrying rails and electric conducting members on a locomotive or car adapted to engage a current carrying rail of the track, a movable stop mechanism comprising insulated means for moving said electric conducting members out of engagement with said rail to break the circuit to and stop the locomotive or car as it passes over a prede- 60 termined portion of the track of the railway, and said stop mechanism being in operative connection with a signal post construction.
- In testimony that I claim the foregoing as my invention I have signed my name in 65 presence of the subscribing witnesses this 20th day of January 1921.
